CLAIM

The ornamental design for a cabinets, as shown and described.

DESCRIPTION

FIG. 1 is a first perspective view of a cabinet according to a first embodiment showing the new design;

FIG. 2 is a second perspective view thereof;

FIG. 3 is a third perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and

FIG. 9 is a bottom view thereof;

FIG. 10 is a first perspective view of a cabinet according to a second embodiment showing the new design;

FIG. 11 is a second perspective view thereof;

FIG. 12 is a third perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof; and

FIG. 18 is a bottom view thereof;

FIG. 19 is a first perspective view of a cabinet according to a third embodiment showing the new design;

FIG. 20 is a second perspective view thereof;

FIG. 21 is a third perspective view thereof;

FIG. 22 is a front view thereof;

FIG. 23 is a rear view thereof;

FIG. 24 is a left side view thereof;

FIG. 25 is a right side view thereof;

FIG. 26 is a top view thereof; and,

FIG. 27 is a bottom view thereof.

The broken lines shown in the drawings are for the purpose of illustrating environmental structure and form no part of the claimed design.
